DOUBLE TAPERED STEEL POST

Gerald G. Greulich, Mount Lebanon, Pa.

Application July 25, 1936, Serial No. 92,659

4 Claims. (Cl. 189—23)

This invention relates to steel posts generally and particularly to such posts for highway guards.

The principal object of the invention is to make such a post in which the metal is distributed to provide the greatest stress resisting area at the critical point and also to secure a long life against corrosion.

Other objects and advantages will become apparent as the description proceeds, in which:

Figure 1 is a side elevation of the assembled post showing the double thickness at the ground line,

Figure 2 is an elevational view at right angles to Figure 1,

Figure 3 is a section on line III—III of Figure 1, Figure 4 is a section on line IV—IV of Figure 1, Figure 5 is a section on line V—V of Figure 1,

Figure 6 is a section on line VI—VI of Figure 1,

Figure 7 is a detailed section showing the manner of connecting the complementary sections together.

In the drawing, the post comprises complementary sections including an upper section 2, a lower section 4 arranged in abutting relation to form, at the ground line, an intermediate reinforced section 5 having a double thickness of metal.

The upper section 2 comprises a conical member gradually tapered throughout its length and provided with flanges 3. These flanges 3 extend from the uppermost or free end of said section and taper toward the ground line to form an increased flange width 6 above and below the ground line.

The lower section 4 comprises a cylindrically shaped cross-sectional member provided with flanges 9 increasing in width at the ground line, said flanges tapering downwardly from the ground line to coincide with the side walls 10 of said section 4 at a point below the ground line, as clearly indicated in Figure 2 of the drawing.

The complementary sections 2 and 4 of the post, when abutted in end-to-end relationship with the increased flange areas 6 and 9 at the ground line and welded together as indicated at 12, produce a unitary structure having the greatest area and thickness of metal at the ground line, thereby assuring longer life for the post against corrosion and strains. The upper section 2, being conically shaped, tapers toward its other end to produce a relatively smaller area at the top of the post where the least area is needed. The top section 2 is large enough to accommodate all types of rail or cable fastenings and is easily visible. The lower section 4, being cylindrically shaped, is cut away

from the point where the flanges coincide with the side walls 10 toward its opposite end to produce a relatively narrow cross-sectional area to facilitate driving of the post in the ground without distortion of the metal and with a minimum disturbance to the soil. The wide areas 13 of the lower section, being in contact with the ground, maintain the lateral soil pressures to a relatively low value under impact, while the piercing end 14 of the section 4 is so shaped that it facilitates keeping the post in alignment during the driving action and keeps the force required for penetration of the soil to a minimum.

The upper section 2 is provided with the desired bolt hole openings 15 for securing a cable (not shown) on the post by means of any conventional fastening device.

The complementary sections 2 and 3 have their ends folded back upon said sections, as shown at 16 and 17, respectively, to provide a double thickness of metal adjacent the ground line. The folded back portions of the upper and lower post sections are aligned to abut each other and are welded together at the point of abutment in any conventional manner. The assembled post construction is then coated with zinc or the like which makes the same highly impervious to corrosion at the ground line.

While I have shown and described the preferred shape for sections 2 and 4, it is to be clearly understood that the sections may be of other shapes; such as, for example, multi-sided constructions in cross-section to produce a flat side for receiving the cable fastening means instead of the conical shape, as shown in the drawing, 35 The sections may be rectangular, hexagonal or a five-sided construction.

It is, therefore, apparent that a post constructed in accordance with the present invention has considerable advantages and design for use as a highway guard rail post, in that the greatest metal area and greatest thickness is at the ground line or point of greatest stress. Having the double thickness at the ground line assures longer life against corrosion.

While I have shown and described one specific embodiment of the present invention, it will be understood that I do not wish to be limited exactly thereto, since various modifications may be made without departing from the scope of the invention as defined by the following claims.

I claim:

1. A steel post comprising an upper section, a lower section and a ground engaging section having a double thickness of metal formed by

folding the ends of said sections back on themselves.

2. A steel post comprising an upper section, a lower section and a ground engaging section having a double thickness of metal formed by folding the ends of said sections back on themselves, said upper and lower sections being welded together.

3. A steel post comprising an upper section, a lower section and a ground engaging section having a double thickness of metal formed by folding the ends of said sections back on them-

selves each of said sections being substantially U-shaped in cross-section.

4. A steel post comprising an upper section, a lower section and a ground engaging section having a double thickness of metal formed by folding the abutting ends of said sections back on themselves, said upper and lower sections being substantially U-shaped in cross-section and welded together at the point of abutment formed by the double thickness of metal.

10

GERALD G. GREULICH.
